UNITED STATES PATENT OFFICE

WILLIAM C. EPSTEIN, OF DAYTON, OHIO, ASSIGNOR TO THE DUO-TOR MANUFACTURING COMPANY, OF DAYTON, OHIO, A CORPORATION OF OHIO

INCINERATOR

Application filed October 19, 1931. Serial No. 569,578.

This invention relates to an incinerator for garbage or the like and more particularly to such an incinerator combined with a water heater.

5 One object of the invention is to provide an incinerator with an improved hopper which will cause the material therein to be quickly dried and burned.

A further object of the invention is to 10 provide such a hopper which will efficiently transmit the heat from the burning material in the hopper to the water in the heating element.

A further object of the invention is to 15 provide a hopper of such a character that the vapors from the burning material will not be condensed and distillate deposited on the water heating element or other parts of the apparatus.

20 A further object of the invention is to provide such a hopper which will be simple in its construction, inexpensive to build and light in weight.

A further object of the invention is to 25 provide a combination water heater and incinerator with a top structure which will properly proportion the draft between the combustion chamber and the flues of the water heater.

30 A further object of the invention is to provide a combination water heater and incinerator with a top structure of such a character that the various parts of the apparatus are readily accessible for cleaning.

35 Other objects of the invention will appear as the apparatus is described in detail.

In the accompanying drawings Fig. 1 is a vertical sectional view taken centrally through a combined incinerator and water heater embodying my invention; Fig. 2 is a top plan view of a portion of the apparatus shown in Fig. 1; Fig. 3 is a horizontal section taken through a part of the apparatus on the line 3—3 of Fig. 1; Fig. 4 is a transverse section taken through the hopper on the line 4—4 of Fig. 1; and Fig. 5 is a similar view of a slightly modified form of hopper.

50 In these drawings I have illustrated one embodiment of my invention and have shown

the same in connection with a combined incinerator and water heater of the type shown and described in my Patent No. 1,794,947 granted to me on March 3, 1931, but it will be understood that this particular embodiment has been chosen for the purposes of illustration only and that the apparatus may take various forms without departing from the spirit of the invention.

55 In the construction here illustrated the apparatus comprises an annular water tank or water heating element 6, the central opening 7, which extends entirely through the tank, constituting a combustion chamber within which the garbage or other material to be consumed may be supported and burned. The outer wall of the tank is insulated in the usual manner, as shown at 8, and this outer wall projects some distance beyond the bottom 9 of the tank and 60 is supported upon a suitable base 10. Carried by the base and arranged beneath the combustion chamber is a gas burner 11. The supply of fuel to the gas burner is automatically controlled to cause the same to 65 operate at intervals in accordance with the temperature of the water of the tank but this automatic control forms no part of the invention and inasmuch as it is well known it need not be here illustrated.

80 Supported within the combustion chamber 7 is a suitable container for garbage or other material to be consumed, herein referred to as a hopper. This hopper comprises two shells of thin metal arranged one within the other and supported in fixed relation one to the other. The outer shell 12 is of a diameter only slightly less than the interior diameter of the combustion chamber, just enough clearance being left between these parts to 85 permit the hopper to be inserted in and removed from the combustion chamber and to provide for such minor variations in the size of the parts as may occur in the normal manufacturing processes. This outer shell 90 serves as a support for the hopper as a whole and has at its upper end an outwardly extending flange 13 which overhangs the fixed part of the apparatus and supports the hopper within the combustion chamber. The inner 95 100

shell 14 is of a diameter somewhat less than the diameter of the outer shell and is provided with longitudinal parts or ribs 15 extending outwardly and having their outer edges in contact with or close to the outer shell. Preferably these ribs are hollow so that they may constitute channels or passageways for air and products of combustion within the inner shell. In the preferred construction the shell is formed of sheet metal and longitudinal portions thereof are bent outwardly at intervals about the same to form the ribs and the side walls of each rib converge outwardly and are connected at their outer edges. These ribs being in engagement with or close to the outer shell and being spaced one from the other form channels 16 between the inner shell and the outer shell which are open at both their lower and upper ends to permit of the passage of the products of combustion through the same. If desired, the inner shell may be provided with openings 17 between adjacent ribs to connect the corresponding channels with the interior of the shell. The inner shell of the hopper may be conveniently formed from corrugated sheet metal and, as shown in Fig. 4, it is formed from sheet metal having corrugations of the usual form. In that form shown in Fig. 5 the inner shell, which is indicated at 18, has especially formed corrugations 19, which are V-shaped in cross section and which have a line contact with the outer shell somewhat narrower than the contact between the corrugations 15 of Fig. 4 and the outer shell. Otherwise the two constructions are the same. The inner shell has secured to its lower end an extension or basket 20 provided at its lower end with a grate supporting structure 21a. This lower portion 20 and grate structure 21 are subjected to the direct action of the flame from the burner and are therefore preferably made of metal having high heat resisting qualities and are detachably connected one to the other and to the inner shell of the hopper so that either or both may be removed and renewed without renewing the hopper as a whole. It will be noted that the basket 20 extends into the inner hopper and being cylindrical in form does not close or interfere with the channels 16.

The outer wall of the tank and its insulated covering 8 project some distance above the top wall 21 of the tank and a top plate 22 rests upon the upper edge of this outer wall, the plate having a downturned flange 23 positioning the same thereon. Depending from the top plate and, in the present instance, cast integral therewith, is a hollow structure 24 which forms an outlet chamber or smoke box leading to an outlet or flue 25. This hollow structure is spaced from the top wall 21 of the tank so that it does not close the upper ends of the flues 26 which extend through

the tank. It is provided in its side wall with openings 27 through which the products of combustion may enter the same. It is also provided in its bottom wall with an opening 28 through which the upper end of the outer shell of the hopper extends and the flange 13 of that outer shell rests upon this bottom wall to support the hopper. In the present construction the bottom wall is depressed about the opening 28 and the flange 13 rests on this depressed portion. The flange 13 is shown in the form of a supporting member or ring separate from the outer shell of the hopper and having depending lugs 29 secured to that shell, thus avoiding any substantial obstruction of the channels 16. The top plate 22 is provided with a relatively large opening which, in the present instance, is substantially coincident with the top of the hollow structure 24, as shown at 30. This opening is closed by a top plate 31 which is provided with the outlet 25 for the products of combustion and with a filling opening 32 through which material may be deposited in the hopper. In the present construction the top plate is provided with a depressed portion 33 about the opening 30 therein and the closure plate rests on this depressed portion of the top plate so that the upper surfaces of the two plates are substantially flush. Arranged within the hollow structure or outlet chamber 24 is a chute 34 to guide the material from the inlet opening 32 to the hopper. This chute is separate from the hopper and is supported by the supporting member or ring 13 for the outer shell of the hopper. This supporting member is provided with recesses 35 arranged to receive lugs 36 on the chute and correctly position the same with its lower end in line with and, if desired, resting upon the inner shell of the hopper. The upper portion of the chute is flared and is of such a size and shape that it extends beneath both the outlet 25 and the filling opening 22 in the closure plate 31 but the upper edge of the chute is spaced from the closure plate and from the side walls of the hollow structure so as to permit the passage of products of combustion from the hollow structure to the outlet. Preferably the closure plate 31 is provided about the filling opening with a depending flange 37 which extends to a line near the upper level of the edge of the chute to prevent any of the material deposited in the chute from escaping into the hollow structure outside of the chute. The filling opening in the closure plate is closed by a lid 38 which, in the present instance is pivotally mounted on the closure plate and is provided with a baffle 39 spaced from the lower surface thereof to prevent excessive heating of the lid. Further, if desired, the outlet 25, which leads to the stack or chimney, may be provided with a grid 40 to prevent 130

large pieces of burning paper or other material from passing into the stack.

The arrangement of the outlet leading to the stacks is such as to bring the outlet 5 comparatively close to the hopper and to provide for the direct flow of the products of combustion from the hopper to the outlet. It will be apparent that with the top structure arranged as shown the products of combustion 10 passing through the flues 26 of the water tank will enter the space above the tank and pass through the openings 27 into the outlet chamber or smoke box. The products of combustion passing through the channels 16 between the two shells of the hopper will directly enter the outlet chamber and pass about the upper edge of the chute to the outlet, and the products of combustion 15 passing from the upper end of the inner shell of the hopper will pass through the chute directly to the outlet. This arrangement enables the draft to be properly proportioned between the flues in the water tank, on the one hand, and the hopper, on the 20 other hand, thereby enabling the structure to be so arranged as to provide a most efficient heating of the water and drying and burning of the material in the hopper. The closure plate and the chute are readily removable, thus permitting the hopper to be lifted 25 bodily from the combustion chamber and also permitting the cleaning of soot or the like from the outlet chamber. This soot is brushed directly into the hopper and finds 30 its way to the lower end of the hopper and to the ash pan 41 arranged beneath the burner. Any material which may adhere to the chute will be dried and eventually consumed by the products of combustion passing 35 through the chute.

The construction of the hopper is such as to provide for a quick drying and burning of the garbage or material therein, a more efficient transmission of heat from the hopper to the water tank and the prevention of the deposit of distillate on the inner wall of the water tank. When garbage or the like is deposited in the inner shell of the hopper it may or may not fill the hollow ribs, and 45 this depending upon the character and softness of the material. Ordinarily the ribs will not be filled completely, this being particularly true of ribs of the shape shown in Fig. 5. When the ribs are not completely filled 50 passageways will be formed near the outer parts of the ribs through which air and products of combustion may pass, thus expediting the drying of the material and subsequently causing the more rapid burning thereof. 55 If the hollow ribs are completely filled with material the material therein will be dried more rapidly than will the material in the body of the hopper because of the application of heat directly to the side walls of the 60 ribs. As the material in the ribs dries it will

shrink and thus withdraw from the narrower portions of the ribs and provide channels for the passage of air and products of combustion, and this dried portion will quickly burn, thus enlarging these channels and increasing the efficiency of the operation. The 70 burning of the material in the hopper will quickly heat the inner shell, which is of relatively thin metal and because of the burning of the material in or adjacent to the hollow ribs the heat will be concentrated in these ribs and will be transmitted thereby to the outer shell with which the ribs are usually in line contact, thereby heating this outer shell. The outer shell is spaced a very slight 75 distance from the wall of the combustion chamber, that is, the inner wall of the water tank, and may in places be in contact with that wall and therefore the heat from the outer shell of the hopper will be transmitted 80 to the tank and the heat generated in the hopper by the burning of material therein will be utilized very efficiently for the heating 85 of the water. Even when the hopper is empty and no material is burning therein the 90 arrangement of the shells and the ribs will increase the thermal efficiency of the device and cause the products of combustion, passing through the channels 16 between the two shells and through the empty inner shell, to 95 heat the ribs and the outer shell and this heat will be efficiently transmitted to the water tank.

In incinerators as heretofore constructed the vapors which are given off by the drying and burning material in the hopper will be condensed in part by contact with the relatively cool wall of the water tank or other water heating element and a distillate will be deposited upon the wall of the tank, or on 100 other parts of the apparatus, which will harden and accumulate to such an extent that it must eventually be scraped off. With the construction of the hopper here described the condensation is reduced to a minimum and 105 any distillate that is deposited on any part of the apparatus is quickly burned off. It will be noted first that because of the arrangement of the two shells of the hopper little, if any, of the products of combustion will 110 come directly in contact with the wall of the combustion chamber. The outer shell of the hopper is heated quickly to such a temperature that there will be no tendency of the vapors or gases to condense thereon but on 115 the contrary the gases or vapors will be largely if not completely consumed by this heat. Should any of the vapors or gases given off by the garbage during the drying process, as when the material is drying under 120 the action of the hot water in the tank and the burner is not in operation, be condensed and deposited on the outer shell of the hopper this deposit will be quickly burned off 125 when the burner comes into operation and the 130

material within the hopper burns. Any such distillate which may be deposited on the lower parts of the hopper or combustion chamber will be quickly burned off by the flame from the burner. Consequently the apparatus is at all times kept free from accumulations of distillate or the like.

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. In an apparatus of the character described, comprising a water tank having an opening therethrough constituting a combustion chamber; a container for material to be consumed mounted in said combustion chamber and comprising an outer shell supported in proximity to the inner wall of said tank, and an inner shell supported within and spaced from said outer shell and having hollow longitudinal ribs spaced apart about the same, said ribs having open communication with the interior of said inner shell and having their outer edges closed and arranged close to said outer shell.
2. In an apparatus of the character described comprising a water tank having an opening therethrough constituting a combustion chamber; a container for material to be consumed mounted in said combustion chamber and comprising an outer shell supported in proximity to the inner wall of said tank, and an inner shell supported within and spaced from said outer shell and having hollow longitudinal ribs spaced apart about the same, said hollow ribs being open at both ends and having open communication with the interior of said inner shell and having their outer edges closed and arranged close to said outer shell.
3. In an apparatus of the character described comprising a water tank having an opening therethrough constituting a combustion chamber; a container for material to be consumed mounted in said combustion chamber and comprising an outer shell supported in proximity to the wall of said tank and an inner shell supported within and spaced from said outer shell and having a series of longitudinal hollow ribs spaced about the same and in open communication with the interior thereof, the side walls of each rib converging outwardly and having their outer edges connected one to the other and arranged close to said outer shell.
4. In an apparatus of the character described comprising a water tank having an opening therethrough constituting a combustion chamber; a container for material to be consumed mounted in said combustion chamber and comprising an outer shell supported

in proximity to the wall of said tank and an inner shell formed of corrugated sheet metal with the corrugations extending lengthwise thereof, and having the outer corrugations arranged close to said outer shell.

5. In an apparatus of the character described comprising a water tank having an opening therethrough constituting a combustion chamber; a container for material to be consumed mounted in said combustion chamber and comprising an outer shell supported in proximity to the wall of said tank and an inner shell supported within and spaced from said outer shell and having a series of hollow longitudinal ribs in open communication therewith and having their outer edges close to said outer shell, said ribs being spaced apart to form channels between the same and said inner shell, having openings between adjacent ribs to connect the corresponding channels with the interior of said inner shell.

6. In an apparatus of the character described, a water tank having a vertical opening forming a combustion chamber and having its outer wall extended above the top wall thereof, a top plate supported on said outer wall and having an opening therethrough, a hopper supported in said combustion chamber beneath the opening in said top wall, a chute supported below said top plate in line with the opening therein and leading to said hopper, and a movable closure for said chute.

7. In an apparatus of the character described, a water tank having a vertical opening forming a combustion chamber and having its outer wall extended above the top wall thereof, a top plate supported on said outer wall and having an opening therethrough in line with said combustion chamber, a hopper supported in said combustion chamber, a chute separate from said hopper removably supported below said top plate and having its lower end arranged to discharge into said hopper, and a movable closure for said chute.

8. In an apparatus of the character described, a water tank having a vertical opening forming a combustion chamber and having its outer wall extended above the top wall thereof, a top plate supported on said outer wall and having an opening therethrough in line with said combustion chamber, a hopper supported in said combustion chamber, a chute removably supported above said hopper with its upper end in line with said opening in said top plate, and a closure for the opening in said top plate.

9. In an apparatus of the character described, a water tank having a vertical opening forming a combustion chamber and having its outer wall extended above the top wall thereof, a top plate supported on said outer wall and having an opening therethrough in line with said combustion cham-

ber, a hopper mounted in said combustion chamber and comprising an outer shell and an inner shell, a supporting member connected with said outer shell and with said 5 top plate, a chute supported by the supporting member for said outer shell with its upper end in line with the opening in said top plate and its lower end in line with said inner shell, and a closure for the opening in said 10 top plate.

10. In an apparatus of the character described, a water tank having a vertical opening forming a combustion chamber and having its outer wall extended above the top 15 wall thereof, a hopper supported in said combustion chamber, a plate supported on said outer wall and having an opening therethrough, a closure plate for said opening supported by said top plate and having an 20 opening therethrough, a chute supported beneath said closure plate in line with the opening therein and arranged to discharge into said hopper, and a movable closure for said chute mounted on said closure plate.

25. 11. In an apparatus of the character described, a water tank having a vertical opening forming a combustion chamber, having its outer wall extended above the top wall thereof and having passageways for the 30 products of combustion, a burner beneath said tank, a top plate supported on said outer wall of said tank, spaced from the top of said tank and having an opening therethrough, a hollow structure depending from 35 said top plate, forming an outlet chamber for products of combustion and having openings in the side and bottom walls thereof, a hopper supported in said combustion chamber by said structure, a chute supported in 40 said hollow structure and arranged to discharge into said hopper, and a movable closure for said chute.

12. In an apparatus of the character described, a water tank having a vertical opening 45 forming a combustion chamber, having its outer wall extended above the top wall thereof and having passageways for the products of combustion, a burner beneath said tank, a top plate supported on said outer 50 wall of said tank, spaced from the top of said tank and having an opening therethrough, a hollow structure depending from said top plate, spaced from the passageways in said tank, having openings in the side and 55 bottom walls thereof and having an outlet, a hopper mounted in said combustion chamber, and comprising an outer shell and an inner shell, said outer shell extending through the bottom opening in said hollow 60 structure and having supporting connection with said structure, a chute supported within said hollow structure in line with the bottom opening therein, leading to the inner shell of said hopper and having communication with the interior of said hollow structure, and a movable closure for said chute.

ture, and a movable closure for said chute.

13. In an apparatus of the character described, a water tank having a vertical opening forming a combustion chamber and having its outer wall extended above the top 70 wall thereof and having passageways for the products of combustion, a hopper supported in said combustion chamber, a burner beneath said tank and said hopper, a top plate supported on said outer wall of said tank and having an opening therethrough, a hollow structure depending from said top plate about said opening, forming an outlet chamber for products of combustion and having an opening in the side and bottom walls thereof, a closure plate for the opening in said top plate having an outlet for products of combustion and a filling opening for said hopper, a chute supported in said outlet 75 chamber with its lower end in line with said hopper and its upper end arranged beneath said outlet and said filling opening, in said closure plate, and a lid for said filling opening.

14. In an apparatus of the character described, a water tank having a vertical opening forming a combustion chamber, having its outer wall extending above the top wall thereof and having passageways for the products of combustion, a burner beneath said tank, a top plate supported by said outer wall of said tank and having an opening therethrough, a hollow structure depending from said top plate, having its bottom 90 wall spaced from the top of said tank and having openings in the side and bottom walls thereof, a hopper arranged in said combustion chamber and comprising an outer shell, an inner shell supported by said outer shell and a supporting member connected with said outer shell and having supporting engagement with said hollow structure about the opening in the bottom wall thereof, a closure plate for the opening in said top plate having an outlet for products of combustion, and a filling opening for said hopper, a chute supported within said hollow structure by said supporting member, having its lower end in line with said hopper and having its upper end spaced from said closure plate and in line with both said filling opening and said outlet, and a lid for said filling opening.

15. In an apparatus of the character described, comprising a tank having an opening therethrough constituting a combustion chamber; a container for material to be consumed mounted in said combustion chamber and comprising inner and outer shells arranged one within the other and spaced apart, one of said shells having a plurality of longitudinal ribs arranged in heat transmitting relation to the other shell, said ribs being spaced apart to divide the space between said shells into channels which are open at their upper and lower ends.

16. In an apparatus of the character described, comprising a tank having an opening therethrough constituting a combustion chamber; a container for material to be consumed mounted in said combustion chamber and comprising inner and outer shells arranged one within the other and spaced apart, one of said shells having a plurality of longitudinal ribs arranged in heat transmitting relation to the other shell, said ribs being spaced apart to divide the space between said shells into channels which are open at their upper and lower ends, said inner shell having openings to connect the space between said shells with the interior of said inner shell.
17. In an apparatus of the character described, comprising a tank having an opening therethrough constituting a combustion chamber; a container for material to be consumed mounted in said combustion chamber and comprising an outer shell supported in proximity to the inner wall of said tank, and an inner shell supported within and spaced from said outer shell and having ribs extending longitudinally thereof with their outer edges in heat transmitting relation to said outer shell and spaced apart to form channels between said shells, said channels being open at both ends.
18. In an apparatus of the character described comprising a tank having an opening therethrough constituting a combustion chamber; a container for material to be consumed mounted in said combustion chamber and comprising an outer shell supported in proximity to the inner wall of said tank, and an inner shell supported within and spaced from said outer shell and having ribs extending longitudinally thereof with their outer edges in heat transmitting relation to said outer shell and spaced apart to form channels between said shells, said channels being open at both ends, said inner shell having openings to connect the interior thereof with the space between said shells.
19. In an apparatus of the character described, comprising a tank having an opening therethrough constituting a combustion chamber; a container for material to be consumed mounted in said combustion chamber and comprising an outer shell of thin metal supported in proximity to the inner wall of said tank, and an inner shell of thin metal arranged within and spaced from said outer shell and having longitudinal portions thereof bent outwardly and having relatively narrow line contact with said outer shell, said longitudinal portions being spaced apart to divide the space between said shells into channels which are open at their ends.
20. A hopper adapted to be mounted in the combustion chamber of a garbage incinerator or the like and comprising a thin inner shell to receive the material to be consumed, and a thin outer shell arranged about and spaced from said inner shell, one of said shells having a plurality of longitudinal ribs arranged with their free edges in heat transmitting relation to the other shell and spaced apart to divide the space between said shells into channels which are open at both ends.
21. A hopper adapted to be mounted in the combustion chamber of a garbage incinerator or the like and comprising a thin inner shell to receive the material to be consumed, and a thin outer shell arranged about and spaced from said inner shell, one of said shells having a plurality of longitudinal ribs arranged with their free edges in heat transmitting relation to the other shell and spaced apart to divide the space between said shells into channels which are open at both ends, said inner shell having openings to connect the interior thereof with the space between the two shells.
22. A hopper adapted to be mounted in the combustion chamber of a garbage incinerator or the like and comprising a thin inner shell to receive the material to be consumed, said shell having a plurality of outwardly extending hollow ribs arranged lengthwise thereof and having open communication with the interior thereof, and a thin outer shell mounted about said inner shell in heat receiving relation to the outer edges of said ribs.
23. A hopper adapted to be mounted in the combustion chamber of a garbage incinerator or the like and comprising a thin inner shell to receive the material to be consumed, said shell having a plurality of outwardly extending hollow ribs arranged lengthwise thereof and having open communication with the interior thereof, and a thin outer shell mounted about said inner shell in heat receiving relation to the outer edges of said ribs, said inner shell having openings between adjacent ribs.
24. A hopper adapted to be mounted in the combustion chamber of a garbage incinerator or the like and comprising an outer shell of thin metal and an inner shell of thin metal mounted within said outer shell to receive the material to be consumed and having longitudinal corrugations contacting with said outer shell.
- In testimony whereof, I affix my signature hereto.
- WILLIAM C. EPSTEIN.
